ELECTRODE HOLDER

Ismail Hakkı, New York, N. Y.

Application June 13, 1942, Serial No. 446,947

3 Claims. (Cl. 176—119)

This invention relates to new and useful improvements in supporting elements, primarily for members which are generally cylindrical in shape, and relates more particularly to an improved support for carbon or other electrodes generally, especially in connection with an arc lamp in a motion picture projector.

Supporting devices of this general character have been objectionable for the reason that their effective life has been short, due largely to the heat generated in the lamp, and also to the rough handling on the part of the operator. Difficulty has also been experienced in providing a socket-like structure which will give adequate and rigid support to the electrode and will also permit the used electrode to be removed and quickly replaced with a fresh one.

It is one of the principal objects of the present invention to provide a support of this type which firmly supports the electrode, which permits simple and rapid replacement of the electrode, and which will have a relatively long life of effective operation, particularly as compared with existing devices.

A further object of the invention is to provide a carbon support which will effect a very considerable saving of the carbon.

Another object of the present invention is to provide a carbon electrode support formed in a plurality of complementary jaw sections which are connected at their lower terminals and which have a suitably formed recess at their upper ends to receive the electrode, the device being free from split clamping bands, easily breakable carbon supporting fingers, and other objectionable elements which have been present in the devices of the art.

In the drawing:

Fig. 1 is a front elevation of the preferred embodiment of the present invention.

Fig. 2 is a side elevation thereof taken at an angle of 90° to that shown in Fig. 1.

Fig. 3 is a broken vertical section of the structure shown in Figs. 1 and 2.

Fig. 4 is a transverse section taken on the line 4—4 of Fig. 1.

Fig. 5 is similar to Fig. 4 but shows the retaining ring having been rotated 90° from the position shown in Fig. 4.

Fig. 6 is a section taken on the line 6—6 of Fig. 1.

Fig. 7 is a broken section through a modified form of the invention.

The preferred embodiment of the present invention is illustrated in Figs. 1 to 4 inclusive and 55

includes a plurality of complementary jaw sections 10 and 11 which are similarly shaped. Each section includes a shank portion 12 which is generally semi-circular in transverse section and is provided with a flattened lower end portion 13 which receives one terminal of a substantially U shaped connecting member 15 formed preferably of flat spring steel and riveted as at 16 to the shank.

Adjacent to but spaced from the upper end of each section is an enlarged collar portion 17 and a further enlarged portion 18 immediately above collar portion 17. The outer surface of portion 18 may be knurled or otherwise rendered non-smooth as shown at 19, since it forms a finger engaging portion.

A recess 22 is formed at the upper end of portion 18 and when the two sections are assembled, as particularly shown in Fig. 3, a circular recess is formed to receive the lower terminal of the carbon electrode 23. The diameter of the complementary recesses 22 is such that the two sections are in spaced relationship when the carbon is inserted therein.

A knurled retaining ring 24 is carried on collar portions 17, such ring being supported on a pin 25 passing through the two sections. This pin may be formed in a single piece as shown in Fig. 3, or it may comprise a plurality of sections as shown in Fig. 1. If it is formed as shown in Fig. 3, one terminal is preferably secured against movement out of its supporting aperture, and in case the pin is formed in two sections, both of such sections will be so secured.

Retaining ring 24 is formed with either a circular or an elliptically shaped aperture 26, the latter form being shown in Figs. 4 and 5. In this way the ring may be rotated 90° from the closed position it occupies in Fig. 4 to the open position of Fig. 6, in which latter position the electrode may be removed. When the ring is in closed position the jaw sections 10 and 11 exert considerable pressure on the electrode and prevent its easy removal. The real compressive action on the electrode comes, however, from the clamping action of supporting members 28 and 29 which are formed with complementary recesses 30 which receive shank portions 12 therebetween. A screw 31 or other similar means retains members 28 and 29 in supporting relationship.

It will accordingly be seen that when the electrode is inserted within the recess formed in the jaw sections 10 and 11 and ring 24 rotated, the electrode is initially secured therein, and that when the shanks are placed between members 28

and 29 or other supporting devices which are conventionally included in motion picture projectors, the electrode is firmly mounted. It may also be removed and replaced with ease.

In Fig. 5 the pin 25 is eliminated entirely and ring 24 employed for retaining the upper ends of the jaw sections in alignment.

The modified form of the invention shown in Fig. 7 includes jaw sections 34 and 35, section 34 having a horizontal aperture 36 supporting a pin 37 which is suitably secured against movement. The opposite end of the pin passes through an aligned aperture 38 of slightly larger diameter than aperture 36. The other arrangements, including the retaining ring 39, are the same as in the first embodiment of the invention.

The materials out of which the device of the present invention may be made are a matter of choice, although it is preferred to form the same from metals which are not seriously affected by the high temperatures to which the device is subjected. A distinct saving in carbon is effected by a device constructed in accordance with the present invention, since it permits a greater portion of the entire stick to be utilized than the existing devices of this general character.

It will be readily apparent that many changes and modifications in the embodiments of the invention illustrated and described may be made without departing from the spirit of the invention as defined by the appended claims. Also, it will be obvious that the devices of the present invention may have a variety of uses in addition to those specifically enumerated.

What I claim is:

1. A carbon supporting device for motion picture projectors comprising a plurality of complementary jaw sections having complementary recesses at their upper ends to receive and support the carbon, shank portions at the lower ends of said sections, a substantially U shaped member

connecting the lower terminals of the sections and retaining means adjacent to the upper terminals of the sections comprising a retaining ring, having an elliptically-shaped aperture therein, encircling said upper terminals, and supporting means for the retaining ring.

2. A carbon supporting device for motion picture projectors or the like comprising a plurality of complementary jaw sections having complementary recesses at their upper ends to receive and support the carbon, shank portions at the lower ends of said sections which can be received between clamping elements associated with the projector, means connecting the lower terminals of the sections, the upper ends of the shank portions having aligned apertures therein, a pin positioned within said apertures and being secured in one of such apertures, and a retaining ring carried adjacent to the upper terminals of the jaw sections for retaining such sections in substantial meeting engagement.

3. A carbon electrode supporting device for motion picture projectors or the like comprising a plurality of individual jaw members formed with shank portions at their lower ends, means comprising a substantially U shaped element formed of flat metal connecting the lower terminals of the shank portions to permit movement of the jaw members relative to each other, each of said jaw members having complementary recesses extending downwardly from their upper terminals and forming a seat at their lower ends for the lower terminal of the electrode, and means for retaining said jaw members in substantial meeting engagement comprising a retaining ring, having an elliptically-shaped aperture therein, carried on the exterior of the several members, and a support for such ring comprising a pin extending outwardly from the members.

ISMAIL HAKKI.
